UNITED STATES PATENT OFFICE.

CHARLES E. CAMPBELL, OF ASHLAND, OHIO.

DESIGN FOR A WATER-BOTTLE, SYRINGE-BAG, OR SIMILAR ARTICLE.

45,789.

Specification for Design.

Patented May 19, 1914.

Application filed March 16, 1914. Serial No. 825,182. Term of patent 7 years.

To all whom it may concern:

Be it known that I, CHARLES E. CAMPBELL, a citizen of the United States, residing at Ashland, in the county of Ashland and State of Ohio, have invented a new, original, and ornamental Design for a Water - Bottle, Syringe-Bag, or Similar Article, of which the following is a specification, reference being had to the accompanying drawing, forming part hereof.

The figure is a plan view of a water-bottle, showing my new design.

I claim:

The ornamental design for a water-bottle, syringe-bag, or similar article, as shown.

CHARLES E. CAMPBELL.

Witnesses:

W. E. McDOWELL,
CHESTER T. ROE.
